TAILSTOCK CENTER ATTACHMENT FOR
BENCH LATHES

Jakob Koenig, Union City, N. J.

Application October 9, 1942, Serial No. 461,426

4 Claims. (Cl. 82—33)

This invention relates to new and useful improvements in a tail stock center attachment for bench lathes.

More specifically, the invention proposes the construction of a tail stock center attachment for bench lathes characterized by a holder adapted to fit the tail stock of a conventionally constructed bench lathe and which is provided with a reamed aperture into which a desired center of a set of centers is adapted to be engaged in a manner to adapt the holder to accommodate work of different types.

Heretofore, in constructing tail stock centers it has been the practice to form the centers of a size to engage the tail stock of the lathe. This invention proposes the saving of time and saving large quantities of tool steel by providing a single holder engaging with the tail stock of the bench lathe and arranged to selectively receive one of a plurality of small centers to adapt the holder as above described.

A further object of the invention proposes a novel means for releasably holding the centers in position within the holder in a manner to permit the centers to be quickly changed when desired.

It is a further object of this invention to construct the centers of different shapes interchangeable with the holder in a manner to permit the lathe to be quickly set up to accommodate different types of work.

A still further object of the invention proposes a means for adjustably mounting the means for releasably holding the centers in position within the holder in a manner to permit this means to be adjusted to meet the requirements of centers of different lengths.

For further comprehension of the invention, and of the objects and advantages thereof, reference will be had to the following description and accompanying drawing, and to the appended claims in which the various novel features of the invention are more particularly set forth.

In the accompanying drawing forming a material part of this disclosure:

Fig. 1 is a side elevational view of a holder for bench lathes constructed in accordance with this invention.

Fig. 2 is an enlarged vertical sectional view on the line 2—2 of Fig. 1.

Fig. 3 is a perspective view of the center shown in Fig. 1.

Fig. 4 is a view similar to Fig. 3 but illustrating a center of a slightly different shape.

Fig. 5 illustrates the manner in which the centers shown in Figs. 3 and 4 are adapted to be used.

Fig. 6 is a side elevational view of a female center.

Fig. 7 is a view illustrating the manner in which the center shown in Fig. 6 is adapted to be used.

Fig. 8 is a perspective view of still another center adapted to be used in the holder shown in Fig. 1.

Fig. 9 is a view illustrating the manner in which the center shown in Fig. 8 is used.

Fig. 10 is a side elevational view of still another center used for grinding.

Fig. 11 is a similar view to Fig. 10, showing the same center used in a bench lathe.

Fig. 12 is a side elevational view of still another center.

Fig. 13 is a sectional view taken substantially on the line 13—13 of Fig. 12.

Fig. 14 illustrates one manner of using the center shown in Fig. 12.

Fig. 15 is another side elevational view of still another center.

Fig. 16 is a side elevational view similar to Fig. 1 but illustrating a modification of the invention.

Fig. 17 is an enlarged vertical sectional view taken substantially on the line 17—17 of Fig. 16.

The tail stock center attachment for bench lathes, according to this invention, includes a holder 10 formed of cold rolled steel or other suitable unhardened metal and which has a head portion 11 and a smaller tapered shank 12 which is adapted to fit the tail stock of a conventional bench lathe. The holder 10 has a reamed aperture 13 extended inwards from one end of its head portion and which continues into a smaller aperture 14 extending through the shank 12.

A set of hardened tool steel centers are adapted to be selectively engaged in the reamed aperture 13 and means is provided for releasably holding the desired center in position within the reamed aperture 13. This means comprises a pair of set screws 15 threadedly engaged through one side of the head portion 11 of the holder 10. The set screws 15 are so arranged that their inner ends will bear against the flat portion of the tool, engaging into the aperture 13 and securely hold it in position therein.

The set of centers and the manner in which they are to be used in connection with the holder 10 are illustrated in Figs. 3 to 14. The first of these centers 16 is illustrated in Fig. 3 and comprises a shank portion 17 and a reduced tip portion 18 and flat portions 16^a on the said shank portion 17. In Fig. 4 the center 16' comprises a shank portion 17^a and a reduced portion 18^a. The reduced portion 18^a in Fig. 4 is of slightly greater size than the reduced portion 18 in Fig. 3. In Fig. 5, the center 16 is illustrated engaging one end of a piece of work 19 mounted in a bench lathe and a micrometer 20 is illustrated as it would be used for measuring the diameter of the end portion of the work 19. Reducing the size of the tip 18 of the center 16 permits the micrometer 20 to be more easily engaged with the end

portion of the work 19 without removing the work from the centers. In Figs. 6 and 7 the center 16'' is characterized by a shank portion 17^b which is engageable into the reamed opening 13 of the holder 10 and which is provided at each of its ends with female centers 18^b and 18^c. The center 16'' is adapted to be engaged with the holder 10 with either of its ends directed outwards to engage the reduced end of a piece of work 21, as shown in Fig. 7.

In Figs. 8 and 9 a tubular center 16''' is illustrated which is adapted to be engaged into the reamed opening 13 of the holder 10. This center 16''' is adapted to receive one end of a rod 22 which has its other end supported in a spring collar 23 mounted in the opposite end of the bench lathe. The rod 22 is adapted to be used for twisting small springs from a length of piano wire 24.

In Fig. 10 still another center 16'''' is illustrated comprising of a shank portion 17^c and a shaped reduced portion 18^d which may be used with a grind-stone 24^a. This center is shown with annular grooves 16^b which may be engaged by the set screws 15 as shown in Fig. 10, or at a turned 180° position as shown in Fig. 11 for the use of cutting the work 24^b by a cutting tool 24^c in a bench lathe.

In Figs. 12-14 still another center 16''''' is illustrated comprising a holder 25 having a shank portion 26 engageable into the reamed opening 13 of the holder 10. The holder 25 supports a ball bearing ring 27 into which a shank 28 is projecting from a disc 29 is adapted to extend, permitting the disc 29 to rotate freely independently of the holder 25. The disc 29 may be engaged against a piece of disc-like work 31 supported on the face plate 32 of the lathe, as shown in Fig. 14. This permits a cutting tool 33 to be engaged against the exposed face of the disc 31 to work thereon.

In Fig. 15 the disc 29' is illustrated to be in step formation and is adapted to be engaged into tubular work 30 of various diameter. In other respects this form of the invention is similar to that shown in Figs. 12 to 14.

In Figs. 16 and 17 a holder 10' is illustrated which has its rearmost set screw 15^a adjustably supported to be movable relative to the length of the head portion 11 of the holder to engage the rear end of cutting tools 16 of different lengths. The set screw 15^a threadedly engages through a slide 34 mounted between a pair of shims 35 mounted in position within an opening 36 formed in the head portion 11 of the holder 10'. In a loosened condition of the set screw 15^a the slide 34 is movable to a desired position along the length of the opening 36, and when the set screw 15^a is retightened to engage the center 16 the slide 34 will also be securely clamped in its newly adjusted position.

In other respects this form of the invention is identical to the previous form and like parts are identified by like reference numerals.

While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I

claim as new, and desire to secure by United States Letters Patent is:

1. A tail stock center attachment for bench lathes having a holder adapted to fit the tail stock of a bench lathe and having a head formed with a reamed aperture into which a center is engaged, a set screw threadedly engaged through said head to abut said center adjacent its front end, a second set screw for abutting said center adjacent its rear end, and means slidably supporting said second set screw to be movable longitudinally relative to said center to be engageable with the rear end of said center regardless of its length.

15 2. A tail stock center attachment for bench lathes having a holder adapted to fit the tail stock of a bench lathe and having a head formed with a reamed aperture into which a center is engaged, a set screw threadedly engaged through said head to abut said center adjacent its front end, a second set screw for abutting said center adjacent its rear end, and means slidably supporting said second set screw to be movable longitudinally relative to said center to be engageable with the rear end of said center regardless of its length, comprising tracks formed along the sides of an opening formed in said head, a slide slidably engaging said tracks and having said second set screw threadedly engaged therethrough 20 to be movable to desired positions along the length of said opening.

25 3. A tail stock center attachment for bench lathes having a holder adapted to fit the tail stock of a bench lathe and having a head formed with a reamed aperture into which a center is engaged, a set screw threadedly engaged through said head to abut said center adjacent its front end, a second set screw for abutting said center adjacent its rear end, and means slidably supporting said second set screw to be movable longitudinally relative to said center to be engageable with the rear end of said center regardless of its length, comprising tracks formed along the sides of an opening formed in said head, a slide slidably engaging said tracks and having said second set screw threadedly engaged therethrough to be movable to desired positions along the length of said opening, said tracks being formed in the inner faces of a pair of shims mounted along the sides of said opening.

40 4. A tail stock center attachment for bench lathes having a holder adapted to fit the tail stock of a bench lathe and having a head formed with a reamed aperture into which a center is engaged, a set screw threadedly engaged through said head to abut said center adjacent its front end, a second set screw for abutting said center adjacent its rear end, and means slidably supporting said second set screws to be movable longitudinally relative to said center to be engageable with the rear end of said center regardless of its length, comprising tracks formed along the sides of an opening formed in said head, a slide slidably engaging said tracks and having said second set screw threadedly engaged therethrough to be movable to desired positions along the length of said opening, said second set screw when tightened against the rear end of said center also clamps said slide against the top walls of said tracks.

JAKOB KOENIG.
